ATTACHMENT FOR AUTOMOBILES

Charles W. De Porter, Dayton, Ohio

Application March 9, 1938, Serial No. 194,891

4 Claims. (Cl. 240—45)

This invention relates to motor vehicle headlights and more particularly to a headlight provided with a light filtering device.

An object of this invention is to provide an attachment incorporated into the headlight of motor vehicles and other headlights that when adjusted into operative position will filter the light emanating from the source, so as to eliminate glare or reflection from particles of moisture, sleet, hail and the like, tending to obscure vision when white lights are used.

An object of this invention is to provide a filter for the light which may be retracted to a position behind the reflector when not in use.

Another object of this invention is to provide an encasement for the bulb, which encasement filters the light emanating from the headlight.

Another object of this invention is to provide a dual purpose light, having two sources of light, one for use in clear weather and the other for use in inclement weather.

Other objects and advantages reside in the construction of parts, the combination thereof and the mode of operation, as will become more apparent from the following description.

Referring to the drawings, Fig. 1 discloses a longitudinal cross sectional view.

Fig. 2 discloses a cross sectional view taken substantially on the line 2—2 of Fig. 1.

Fig. 3 is a view looking in the direction of the arrow 3 in Fig. 2.

Fig. 4 is a cross sectional view similar to Fig. 1, showing the filter in retracted position.

Fig. 5 discloses a modification.

Fig. 6 discloses a side elevation of the light showing the operating lever.

Fig. 7 is a front view looking in the direction of the arrow 7 shown in Fig. 5.

Fig. 8 is a cross sectional view of the housing taken substantially on the line 8—8 of Fig. 5; but drawn to a smaller scale.

In driving a motor vehicle in inclement weather, especially dark nights when it is foggy, rainy, snowing or sleet, the light emanating from an ordinary incandescent electric light bulb is reflected by the particles of precipitation in the air, causing a glare obscuring or shielding vision, so that the light really obscures vision rather than improves it.

It has been found that by filtering the light through an amber lens, or any other suitably colored lens, there is no glare to speak of caused by such filtered light striking the particles of precipitation. Thus, by filtering the light, driv-

ing in the dark during inclement weather is made much easier than without filtered light.

In the drawings, the reference character 10 indicates the outer shell or casing of a headlight provided with a reflector 12, an electric bulb 14 and a conventional lens 16. With the exception of the reflector, these parts are conventional. The reflector is provided with a pair of horizontal slots 20 joined at the top with an arched slot 22. These slots provide a passage for a light filter 30, having a contour forming a segment of a sphere.

This filter 30 is preferably made from colored glass, as for example, a piece of amber glass. It may be seated in a suitable metallic frame 32, extending around the entire periphery. The filtering lens 30 is mounted upon a pair of sector members 34, fixedly attached to studs 36 and 38. These studs are journaled in bearing 40 and 42 in casing members 44 and 46, attached to the rear of the reflector but within the casing 10.

As many be seen from Figures 1 and 4, casing members 44 and 46 provide a housing for the filter 30 when it is in the retracted position shown in Figure 4. Brushes 48 and 50 mounted in the path of the filter lens 30 wipe dirt and foreign particles from the filter lens as it is actuated from one position to the other, thereby tending to keep the filter lens clean.

The stub shaft 38 projects through the casing 10 and terminates in a suitable lever 54 seated in one of the two notches 56 and 58, shown in Figure 6. As the lever is actuated from the full line position in Figure 6 to the dotted line position, the filter lens 30 is actuated from the position disclosed in Figure 4 to that disclosed in Figure 5.

The stub shaft 38 in some installations terminates within the casing 10 and is then provided with a suitable crank actuated by a suitable driving mechanism such as a Bowden wire terminating on the instrument board. Thus, the driver may shift the filter from one position to the other without stopping the vehicle. In other installations the stub shaft terminates under the hood of the vehicle, so as to enclose and conceal the lever 54. When the lever 54 is located on the outside of the headlight casing 10, it is preferably placed between the headlight and the hood of the vehicle.

When the filter lens 30 is in the position disclosed in Figures 1 and 3, the lower margin of the lens 30 is contoured to snugly fit the base of the reflector 12, so as to completely filter all of the light. Although the sector members 34 have

been shown as made of metal, these may also be made of colored glass, so as to permit the light to pass through these sectors so as to hit the sides of the reflector 12. Whether the sectors 34 are 5 made of metal or of colored glass, all of the light emanating from the light bulb 14 is filtered when the filtering lens 30 is in the position disclosed in Figures 1 and 3. In the past, a portion of the light has been dimmed by shields extending over 10 part of the bulb, similar to that disclosed in the patent to Shaffer No. 1,123,939 patented January 5, 1915; but in this structure, some of the light has been completely shut off and the remainder of the light escapes in its entirety, without being 15 filtered. In the present modification all of the light is filtered, none of the light escaping without being filtered.

In clear weather the filter lens 30 is retracted into the housings 44 and 46 located to the rear of the reflector. When the filtering lens is in 20 this position the white light as it emanates from the incandescent lamp 14 is utilized without filtering.

In the modification disclosed in Figures 5, 7 25 and 8, instead of utilizing a shield or a filtering lens 30, the same result has been obtained by interchanging bulbs or incandescent lamps. This mechanism includes a member 100 provided with a pair of sockets 102 and 104. The socket 102 30 supports an ordinary incandescent electric bulb 106, having one terminal 108 grounded to member 100 and the other terminal 110 connected to a metallic contact strip 112 energized from a wire 114 provided with a terminal 116 contacting a 35 brush 118 connected to the lead 120 completing the circuit to the source of energy which may be either the battery or the generator. With the bulb 106 there is associated a reflector segment 130 snugly fitting a suitable slot in the end of the 40 reflector 132 mounted in the casing 134 provided with a lens 136. The support 100 is fixedly mounted upon the shaft 140 connected to the external lever 54. The support 100 is also provided with a bulb 144 which will filter the light 45 generated by this bulb when it is energized. By actuating the lever 54 from the full line position shown in Figure 6 to the dot-dash position shown in the same figure, the bulb 106 is rotated from the full line position to the dot-dash position 50 shown in Figure 1 and the bulb 144, together with the reflector segment 146, is positioned in the place of the bulb 106 shown in full line in Figure 1. When the bulb 144 having sufficient candle power either for full light or dim light, is 55 rotated into registry with the reflector 132, an amber light is supplied. The bulb 144 is then energized through a metallic clip 150 connected to the lead 156 provided with a contact terminal 158, which has now been rotated through an 60 angle approaching 90°, so that the contact 158 is brought into registry with the brush 118, so as to energize the lamp 144. The lamp 144, when out of operative position, is encased within the housing 170. When the bulb 106 is rotated into 65 the dot-dash position it is encased within the housing member 172, diametrically disposed with respect to the housing member 170. When the assembly is in this position the bulb 106 is de-energized.

70 Housing members 170 and 172 cooperate with the spacer wall 174 and the side walls 176 and 178 to form a dust-proof enclosure to the rear of the reflector 132; but within the housing or casing 134 to protect the part of the lighting system when not in use. The shaft 140 is jour-

nalled in the walls 176 and 178. Thus, the filtering bulb 144, preferably amber in color, may be rotated with the shaft 140 from the position within the casing to the rear of the reflector into operative and filtering position. When in 5 this position the amber bulb 144 is centrally disposed with respect to the reflector 132 much the same as the filtering lens 30 when it is in the position shown in Figures 1 and 2.

Single contact wiring has been shown. For 10 modern electric bulbs for motor vehicles double contacts would be used, one for the bright light filament and another for the dim light filament. The parts of the electric circuit may then be duplicated, making the changes necessary to 15 accommodate the double filament bulbs.

Although the preferred modification of the device has been described, it will be understood that within the purview of this invention various changes may be made in the form, details, 20 proportion and arrangement of parts which generally stated consist in a device capable of carrying out the objects set forth, in the novel parts, combination of parts and mode of operation, as disclosed and defined in the appended 25 claims.

Having thus described my invention, I claim:

1. In a headlight assembly for motor vehicles and the like the combination including a reflector simulating a parabolic reflector, said reflector 30 having a slot having an arcuate portion terminating in a pair of portions lying in parallel planes, a casing housing the reflector and forming a cavity to the rear of the reflector, a shell mounted to the rear of the reflector and registering with the opening therein, said shell being mounted between the reflector and the casing, a shaft pivotally mounted in the shell, electric means centrally disposed with respect to the reflector for generating light, movably mounted 35 means for filtering the light, supporting means including a pair of arcuate sectors fixedly attached to the shaft for supporting said filtering means, said arcuate sectors supporting the filtering means in the shell when not in use, and means for rotating said filtering means through the arcuate portion of the slot from the position within the shell to a position centrally disposed with respect to the reflector and within the reflector so as to filter all the light generated by 40 said electric means, the arcuate sectors rotating through said pair of slot portions when the filtering means is adjusted from one position to the other.

2. In a headlight assembly for motor vehicles 45 and the like the combination including a reflector having an arcuate slot terminating in a pair of slot portions lying in parallel planes, a casing housing the reflector and forming a cavity to the rear of the reflector, a shell mounted to the 50 rear of the reflector and registering with the opening therein, said shell being mounted between the reflector and the casing, a shaft adjustably mounted in the shell, electric means centrally disposed with respect to the reflector 55 for generating a light, and filtering means housed within the shell when not in use, said filtering means including a pair of supporting sectors fixedly attached to the shaft for adjustment therewith, said filtering means being movable 60 from the shell through the arcuate slot portion into a position centrally disposed with respect to the reflector and located in the reflector, and actuating means accessible from the exterior of the casing for adjusting said filtering means so 65 70

that the light emitted from the headlight may be optionally filtered.

3. In a headlight assembly for motor vehicles and the like the combination including a reflector having a slot including an arcuate portion terminating in a pair of side portions disposed in parallel planes, a casing housing the reflector and forming a cavity to the rear of the reflector, a shell mounted to the rear of the reflector and registering with the slot therein, said shell having a pair of concentrically disposed spherical sectors each of which terminates in straight parallel segments cooperating to form a cavity, a source of illumination concentrically disposed 10 with respect to the reflector, filtering means adjustably mounted into operative and inoperative positions disposed between the spherical sectors when in operative position and extending over the light so as to completely filter all of the 15 light emanating from the illuminating source when in operative position, and a pair of sectors for supporting said filtering means, said pair of sectors being adjustably mounted so as to support the filtering means in operative position 20 when in use and to support the filtering means within the shell to the rear of the reflector when the filtering means is in inoperative position, said 25

filtering means passing through the arcuate portion of the slot when advancing from one position to the other, said supporting sectors passing through the side portions of the slot when advancing the filtering means from one position to 5 the other.

4. In a headlight assembly for motor vehicles and the like the combination including a reflector having an arcuate slot terminating in a pair of slot portions lying in parallel planes, a casing 10 housing the reflector and forming a cavity to the rear of the reflector, a shell mounted to the rear of the reflector and registering with the opening therein, said shell being mounted between the reflector and the casing, electric means centrally 15 disposed with respect to the reflector for generating light, and filtering means adjustably mounted, said filtering means including a lens normally disposed in the shell when not in use but adjustably mounted for movement through 20 the arcuate portion of the slot so as to overlie said electric means to filter all of the light emanating from the same, said filtering means contacting the reflector on the side opposite the arcuate portion of the slot when in filtering position. 25

CHAS. W. DE PORTER.
